DESIGN.

—o—
H. MITCHELL.

CARPET.

No. 16,375.

Patented Nov. 10, 1885.

UNITED STATES PATENT OFFICE.

HERBERT MITCHELL, OF WORCESTER, MASSACHUSETTS, ASSIGNOR TO MATTHEW J. WHITTALL, OF SAME PLACE.

DESIGN FOR A CARPET.

SPECIFICATION forming part of Design No. 16,375, dated November 10, 1885.

Application filed September 19, 1885. Serial No. 177,611. Term of patent 3½ years.

To all whom it may concern:

Be it known that I, HERBERT MITCHELL, a citizen of England, residing at Worcester, in the county of Worcester and State of Massachusetts, have invented a new and original Design for Carpets and Similar Fabrics, in such coloring as may be designed; and I do hereby declare that the photographic prints accompanying this specification convey to any one skilled in the art of carpet weaving and manufacture a clear understanding of the same, and is sufficient to enable such person to use my invention.

What I claim as my invention, and desire to secure by Letters Patent, is—

The design for carpets, as shown in the photographic print accompanying this specification.

In testimony whereof I have signed my name to this specification in the presence of two subscribing witnesses.

H. MITCHELL.
